LUBRICATING OIL

Charles C. Towne, Beacon, N. Y., assignor, by
mesne assignments, to The Texas Company,
New York, N. Y., a corporation of Delaware

No Drawing. Application March 8, 1941,
Serial No. 382,335

20 Claims. (Cl. 252—33)

This invention relates to a lubricating oil, and particularly to a motor oil adapted for the lubrication of bearings and cylinders of an internal combustion engine, such as a Diesel engine adapted for heavy duty service in tractors, buses and the like.

This application is a continuation-in-part of my copending application Serial No. 267,918, filed April 14, 1939.

It is an object of the present invention to provide an improved lubricating oil of this character which is not only effective to reduce ring sticking and engine wear, and minimize bearing corrosion in heavy duty service of this character, but is also effective to prevent accumulation of oil ring sludge and lacquer deposits, whereby the engine will remain in satisfactory operating condition over long periods of heavy duty service, such as in a continuous endurance run of 1000 hours or more.

I have now discovered that by the combination of about 0.1-2% by weight of stannous naphthenate with about 0.1-2.0% of a phosphatide, such as lecithin, in a mineral lubricating oil of the character of a motor oil, a superior crank case lubricant accomplishing the objects set forth above and particularly adapted for heavy duty Diesel tractor service is thereby obtained.

In the copending application of Frank W. Hall and Charles C. Towne, Serial No. 223,487, filed August 6, 1938, now issued as Patent No. 2,257,601 of September 30, 1941, there is disclosed and claimed the addition of a lubricating oil of the character of a motor oil of a small proportion of a phosphatide, such as lecithin, to reduce or inhibit lacquer formation and bearing corrosion. While such an oil is highly effective for the purposes intended, it is found that when it is used as a crank case lubricant in long time heavy duty service, such as in a Diesel tractor lubricant, ring sticking may occur in a comparatively short time of the order of 120 hours or less of continuous operation. However, by the combination of controlled and critical small percentages of stannous naphthenate with controlled and critical small percentages of a phosphatide, such as lecithin, these objections are overcome and a superior Diesel tractor lubricant to any heretofore known is thereby produced.

The stannous naphthenate employed is unique in its properties among the metallic naphthenates in not only improving ring sticking and wear resistance qualities, but also in not objectionably affecting bearing corrosion, oxidation, and color change of the oil. This is all the more

unexpected because the metallic naphthenates heretofore suggested for this purpose, such as aluminum naphthenate, uniformly increased the rate of bearing corrosion and have also seriously impaired the oxidation and color stability of the oil. The stannous naphthenate is prepared from partially purified naphthenic acids obtained from petroleum, such as the naphthenic acids of lower molecular weight obtainable from a petroleum gas oil fraction, or the heavier naphthenic acids of higher molecular weight which are obtained from heavy residual mineral lubricating oil. The naphthenic acids may be highly purified although those which are partially purified by methods conventional in the industry such that they have a neutralization number of the order of 100-150 and containing a substantial proportion of non-saponifiable matter, are satisfactory. These acids are neutralized with a caustic soda solution to form sodium naphthenate; and to the solution is then added a stannous salt, such as stannous chloride, in solid form to effect a double decomposition with precipitation of insoluble stannous naphthenate. A water-immiscible organic solvent, such as naphtha or benzol, is added which dissolves the stannous naphthenate; and the mix is allowed to stand and stratify into a water layer containing water-soluble salts and a solvent layer containing the dissolved stannous naphthenate. The layers are then separated, the solvent layer washed several times with water to remove remaining water-soluble salts, and the solvent layer then filtered through an inactive clay to remove suspended matter. The solvent is then stripped by heating to a distillation temperature to recover the stannous naphthenate directly; or, the solvent layer may be mixed with a quantity of mineral lubricating oil prior to or after filtration, and before stripping, and then the solvent stripped off to obtain a lubricating oil concentrate of stannous naphthenate.

The stannous naphthenate composition obtained is found to have a neutralization number varying between about 60 to 90, and has a proportion of the order of 15-25% of non-saponifiable matter originally contained in the partially purified naphthenic acids. This composition is dissolved in the mineral lubricating oil adapted to be used as the motor oil in a proportion to give a stannous naphthenate solid content of about 0.1-2.0% by weight. A preferred proportion range for a Diesel lubricating oil is about 0.5-1.5% by weight.

The phosphatides, or the lecithins as they are frequently called, which are employed herein,

belong to the class of compounds having the general formula:

where R and R' are similar or dissimilar fatty acid radicals such as those derived from stearic, palmitic, oleic acids, etc., and where X represents an amino alcohol group. In the case of lecithin, X or the amino alcohol group is choline

and in the case of cephalin X is colamine

Other types of compounds falling within the class of phosphatides can be employed, such as sphingomyelin. Also metal derivatives or salts of the lecithins can be employed. For example, the free acid group of the compound can be neutralized with alkali, alkaline earth and other bases to form the corresponding salts thereof. A preferred composition for this purpose is commercial soybean lecithin, such as the product known commercially as "Lipoidol" which consists essentially of about equal proportions of lecithin and cephalin with a smaller proportion of soybean oil. Preferably a bleached commercial soybean lecithin is used, such as the product sold commercially as "Colloidol BT" which is commercial soybean lecithin bleached with hydrogen peroxide and dibenzoyl peroxide, or the product sold commercially as "Colloidol HX" which is commercial soybean lecithin bleached with hydrogen peroxide. If desired, the commercial soybean lecithin can be purified by extracting the soybean oil with acetone to obtain the product consisting essentially of lecithin and cephalin. Also, the cephalin constituent can be separated from the lecithin by alcohol extraction, and either the purified lecithin or purified cephalin or mixtures of the two in any desired proportion may be employed for purposes of the present invention. Likewise, phosphatides derived from other sources, such as from the brains and spinal column of cattle and from egg yolk, may be employed. Wherever the expression "phosphatide compound" is used throughout the description and claims, it is to be understood that this includes any of the purified compounds or derivatives thereof falling within this group, as well as any of the comparatively impure mixtures such as the commercial grades mentioned above.

The phosphatide compound is added to the motor oil in a proportion range of about 0.1-2.0% by weight, and in combination with the above-mentioned proportion range of stannous naphthenate a proportion of about 0.1-0.5% of lecithin is preferred for a Diesel lubricant. A very satisfactory method for adding the phosphatide compound to the mineral lubricating oil is to first form a concentrate, such as about a 50% solution of the lecithin or other phosphatide compound in a mineral lubricating oil within the motor oil viscosity range, and then add the concentrate to the mineral lubricating oil in an amount sufficient to give the desired percentage of phosphatide compound therein. Preferably, a concentrate of both the phosphatide and the stannous naphthenate in

lubricating oil, such as a mineral lubricating oil solution containing about 25% by weight of each of the above-named constituents, is prepared, and then added to the bulk of the mineral lubricating oil.

- 10 The modern development of internal combustion engines with extremely small clearances between piston and cylinder wall, has given rise to the problem of so-called varnish or lacquer formation. This lacquer generally appears as a yellowish or reddish brown film which deposits upon the metal surfaces, piston skirt, piston pin relief surface, cylinder wall, etc., during operation of the engine over extended periods of time. Further, the modern development of the new type bearings, including connecting rod and main bearings, which has involved a departure from the old babbitt bearings, and introduced new alloyed bearings of the type of cadmium-silver, copper-lead, etc., has accentuated the problem of bearing corrosion. These problems are particularly accentuated in connection with engines adapted for heavy duty service, such as in Diesel tractor work. Leading manufacturers of Diesel engines and 20 Diesel driven tractors have recognized these problems to be so serious that only special compounded mineral lubricating oil specifically designed for crank case lubrication in such service are recommended for use in these engines.
- 25 30 Special endurance tests have been devised to test the suitability of compounded oils for this service, a typical one being the so-called 1000-hour Caterpillar endurance test. The compounded oil of the present invention is one of a very few oils thus far developed which has satisfactorily withstood this extremely rigorous test, and at the same time has done so with less bearing corrosion on cadmium-silver and copper-lead type bearings than any other oil heretofore known 35 and used for this purpose. Briefly, the Caterpillar endurance test is carried out in a single cylinder Diesel engine operating at 900 R. P. M. with a water jacket temperature of 175° F. running continuously for 1000 hours or until rings 40 are stuck as indicated in the increase in blowby, and in which the crank case oil is drained every sixty hours and fresh oil supplied thereto.
- 45 For purposes of a Diesel engine lubricant, preferably a naphthene base or coastal distillate lubricating oil of the proper viscosity range is selected. The oils are made up into various grades of progressively increasing viscosity, similar to the motor oil grades S. A. E. 10 to S. A. E. 60. By way of 50 example, a Diesel lubricating oil of S. A. E. 20 grade was prepared by warming a straight naphthene-base distillate having a viscosity of about 300 at 100° F. to a temperature of about 150° F., then a stannous naphthenate composition was 55 added and the mix stirred mechanically at this temperature until complete solution was obtained so that the oil contained about 0.5% by weight of the stannous naphthenate. A 50% concentrate of lecithin in mineral lubricating oil was then 60 added and the mix stirred mechanically at a temperature not over 150° F. until a homogeneous solution was obtained and to provide a proportion of 0.5% by weight of lecithin in the oil. A similar Diesel lubricant of S. A. E. 30 grade was prepared in the 65 same manner to contain 0.5% stannous naphthenate and 0.5% lecithin, the base oil in this case being made up of 90% of a naphthene-base lubricating oil of a viscosity of about 750 at 100° F. and 70 75 10% of a naphthene-base oil of a viscosity of

about 300 at 100° F. Typical tests on the resulting oils were as follows:

Tests	S. A. E. 20 Diesel oil	S. A. E. 30 Diesel oil

		0.11

The resulting compounded oils were found to be of satisfactory odor, entirely color stable and to have satisfactory storage stability.

In place of the stannous naphthenate soap, I have found that a stannous sulfonate prepared from mahogany sulfonic acids may also be used satisfactorily in combination with a phosphatide compound in the proportion ranges set forth above. The mahogany sulfonic acids are the oil-soluble acids obtained from the treating of mineral lubricating oil with sulfuric acid, and may be prepared and purified by conventional methods. The stannous soap of these acids is prepared in a manner similar to the preparation of the stannous naphthenate described above by first forming the alkali metal soap of these acids and then adding a solid stannous salt, such as stannous chloride, to effect double decomposition and precipitation of the stannous sulfonate. The resulting stannous sulfonate, preferably employed as a concentrate in mineral lubricating oil, is added to the Diesel lubricant in the manner set forth above for the stannous naphthenate, and in combination with the above-mentioned proportions of a phosphatide, such as lecithin, imparts to the resulting compounded oil improved ring sticking and wear-resisting qualities, as well as minimizing bearing corrosion of either cadmium-silver or copper-lead bearings, and inhibiting oil ring and filter sludge and varnish deposits.

In order to illustrate the effectiveness of the compounded lubricant of the present invention in reducing oil ring sludge in comparison with the base oil, three runs were made on a so-called oil ring sludging test in a C. F. R. Diesel engine operating for each run for thirty-six hours at 1200 R. P. M. with a jacket temperature of 210° F. and a rich fuel mixture fed at the rate of 20 cc. per minute to thereby aggravate sludge formation, the runs first being made on the blank oil and then on the same oil containing .5% stannous naphthenate and .5% lecithin, and finally on the blank oil. The total weight of sludge accumulating in the oil rings was weighed; and this sludge was extracted in each instance with 86° naphtha to separate the naphtha soluble portion or oil from the insoluble portion which is considered as true insoluble sludge. The following results were obtained:

Oil tested	Total sludge— wt. in grams	86° naphtha soluble— wt. in grams	86° naphtha insol- uble—wt. in grams
Blank oil naphthene base S. A. E. 30.	1.510	1.257	0.253
Base oil+.5% stannous naphthenate+.5% lecithin.	0.937	0.904	0.033
Same blank oil.	1.486	1.105	0.381

The following results were obtained in the 75 piston with conventional piston rings. In pre-

above-described 1000-hour Caterpillar entrance run on a naphthene-base S. A. E. 30 oil compounded with 0.5% stannous naphthenate and 0.5% lecithin in comparison with the same base oil compounded with 1.3% of a previously known and approved Diesel oil additive, with respect to engine oil-free sludge deposits on the listed engine parts. The run on the base oil containing 1.3% of said known additive was terminated at the end of 780 hours, and the weights of sludge deposit were interpolated to a 1000-hour basis for comparison:

	Base oil+ 0.5% stannous naphthenate+.5% lecithin—wt. of deposit in grams	Base oil+ 1.3% addi- tive—wt. of deposit in grams

	Underside of piston.....	2.1
	Crank case.....	2.2
		11.7

As illustrative of the effectiveness of the compounded oil of the present invention in reducing bearing corrosion, the following empirical test was used. A special cadmium-silver or copper-lead bushing which is lined with the same alloy as employed in rod bearings of automotive engines was immersed in a pot of the oil to be tested, which oil was heated to a controlled temperature of either 225° F. or 275° F. The oil is continuously circulated between the bushing and its journal by a suitable propeller or "whirligig" for a period of time varying from ten to forty hours. The bushing is weighed before the test and at ten-hour intervals, and the loss in weight is listed in milligrams. The compounded oil of this invention was compared with the same base oil containing a proportion of 1.3% of the above-mentioned additive which had heretofore been approved for this service. The base oil used was a naphthene-base S. A. E. 30 grade. The following results were obtained:

BEARING CORROSION—COPPER-LEAD AT 225° F.

¹ 15 hours.

65 In addition to the 1000-hour endurance test mentioned above, the following additional tests were run to illustrate the effectiveness of the compounded oil of the present invention in reducing ring sticking. In this test, there was employed a single cylinder C. F. R. engine operating at 900 R. P. M. with a 5:1 compression ratio, with 1° spark advance and wide open throttle, the jacket temperature being maintained at 375° F. The engine is equipped with a cast iron solid skirt

70 piston with conventional piston rings. In pre-

paring the engine for testing, the crank case, cylinder and piston are first cleaned thoroughly to remove all deposits and to provide a perfectly clean engine. The engine is then reassembled and the crank case charged with the required amount of oil, generally 3000 cc. The engine is then operated to give maximum power under the conditions set forth above for a period of time, generally eighteen hours. The oil is drained immediately after stopping, the engine allowed to cool for at least three hours, and then the cylinder removed and the piston rings inspected. If the rings are found free, the cylinder and oil replaced and the run continued for an additional eighteen hours, when it is again disassembled and inspected. This procedure is continued until sticking occurs, generally of the top piston ring, or until the run has continued for such a length of time as to be conclusive without actual sticking. If, at any inspection, rings are on the verge of sticking, the additional run may be reduced to twelve hours or less. When a severe ring sticking condition is observed, the sticking time is estimated at some time between that of the final and the preceding inspection. An accuracy of + six hours is generally obtained. The following are the results of runs made on an airplane oil, which is a solvent-refined residual paraffin-base lubricating oil having a S. U. viscosity at 210° F. of about 120, and on the same oil compounded with 5% stannous naphthenate and .5% lecithin:

Oil tested	Ring sticking time in hours
Base airplane oil	40
Base oil + 0.5% stannous naphthenate + 0.5% lecithin	70

In preparing a concentrate of both additives, it is preferable to first charge the mineral lubricating oil, such as a naphthene-base of a viscosity of 300 at 100° F., heat to about 150° F., add the stannous naphthenate and mechanically stir until dissolved. The lecithin is then charged while the temperature is maintained at about 150° F. or slightly below, and again mechanically stirred until a homogeneous solution is obtained. A very suitable concentrate of this character is one containing by weight about 25% stannous naphthenate, 25% lecithin and 50% oil. However, the concentrate can be prepared to contain the additives in either greater or lesser proportions than those specified, but preferably to contain about 20-70% of total additives.

I have further discovered that when small proportions of a phosphatide, such as lecithin, are added to a polyvalent metal soap additive and compounded in lubricating oil, the phosphatide improves the inhibiting characteristics of the metal soaps and renders the compounded oil extremely stable in both operation and storage.

Heretofore these polyvalent metal soaps have been found to have only limited application as lubricating oil additives because of their limited solubility in various base oils and their instability in operation and in storage. It has been found that these metal soaps, even though soluble in a particular base oil, are very apt to separate from the oil even on short term storage. Since it is very seldom that a freshly compounded oil is immediately put into use, the oil must be sufficiently stable to withstand storage, either light or dark, of upward of one month.

Another factor which has been found prevalent among the polyvalent metal soaps is their limited solubility in the various base oils. For example, a metal soap may be sufficiently soluble in a naphthene base oil to be used advantageously therewith and still be comparatively insoluble in either a paraffin base oil or a paraffin naphthene blend oil. With the addition of small proportions of a phosphatide to these metal soaps, their solubility in a hydrocarbon oil has been increased and the resulting lubricant found to be stable for long periods of storage.

Among the polyvalent metal soaps which are affected by the addition of a phosphatide are the polyvalent metal soaps of fatty acids, modified fatty acids, sulfonic acids, and naphthenic acids. These heavy metal soaps may be the aluminum, barium, calcium, cadmium, strontium, mercury, iron, zinc, copper, cobalt, nickel, manganese, magnesium, tin and lead salts of saturated or unsaturated fatty acids obtained from fats, oils, resins and waxes, or substituted derivatives thereof containing halogen, sulfur and nitrogen substituents, together with their alkyl and aralkyl derivatives.

The phosphatide compound is added to the motor oil in a proportion range of from 0.1-2.0% by weight, and when used in combination with the above-mentioned polyvalent metal soaps the preferred proportion range is dependent upon the particular soap and the particular base oil to which it is added. For example, in preparing a Diesel lubricant with a combination of calcium dichlor stearate and lecithin, the preferred range in a paraffin base oil is 0.1-3.0% by weight of calcium dichlor stearate with 0.5-1.25% by weight of lecithin. When using the above preferred proportion range of calcium dichlor stearate in a naphthene-paraffin blend oil with a 1:1 ratio, the preferred proportion range of lecithin is between 0.1% and 1.0%, and for a naphthene base oil containing the same percentage of calcium dichlor stearate the preferred proportion of lecithin is in a range between 0.1 to 0.75%.

In order to exemplify the effect of the phosphatide of the present invention on a polyvalent metal soap with regard to its solubility in a hydrocarbon oil and the resulting stability on storage, the following data were obtained, using calcium dichlor stearate as the metal soap with various base oils:

Base oil	Calcium dichlor stearate	Lecithin	Appearance of sample after—			
			Per cent	Per cent	Two months	Five months
Naphthene+paraffin (1:1) S. A. E. 30.....	2.5	None	Definite separation of additive.....			Definite separation of additive.....
Do.....	2.5	0.1	Clear; no haze or separation of additive.....			Slight haze in oil.....
Naphthene S. A. E. 30.....	4.44	None	Precipitate.....			
Do.....	4.44	0.1	Clear; no haze or separation of additive.....			
Do.....	3.25	1.0	do.....			Very slight haze.....
Do.....	3.25	0.125	do.....			

As an example of the effect of the phosphatide on the inhibiting properties of the metal soap, the following empirical corrosion test was made, using calcium dichlor stearate as the corrosion inhibitor. In this test a copper-lead bearing specimen, incased in a special non-wear bushing and rotatably mounted on a stainless steel shaft, was immersed in a glass pot of the oil to be tested. The tested oil was heated to a controlled temperature of either 250° F. or 350° F. and continuously circulated between the bearing specimen and the shaft for periods of time varying from two to ten hours. The bearing specimen was weighed before the test and at the end of the ten hour period and the loss in weight recorded in milligrams. The base oil used was a naphthene base S. A. E. 30 grade. The results of two runs at 250° F. and 350° F. respectively, are presented:

BEARING CORROSION—COPPER LEAD (10 HOURS)

Weight loss in mgs.

Oil tested	250° F.	350° F.
Base oil + 4.44% calcium dichlor stearate	146,159	233,245
Base oil + 4.44% calcium dichlor stearate + 0.2% lecithin	95,122	174,187

Obviously many modifications and variations of the invention may be made without departing from the spirit and scope thereof, and therefore only such limitations should be imposed as are indicated in the appended claims.

What I claim is:

1. A motor oil adapted for crank case lubrication of an internal combustion engine comprising a mineral lubricating oil within the motor oil viscosity range containing about 0.1-2.0% by weight of a stannous soap selected from the group consisting of stannous naphthenate and stannous sulfonate.

2. A Diesel lubricating oil adapted for crank case lubrication of a Diesel engine comprising a naphthene base lubricating oil within the motor oil viscosity range containing about 0.1-2.0% by weight of lecithin and about 0.1-2.0% by weight of stannous naphthenate.

3. A Diesel lubricating oil adapted for crank case lubrication of a Diesel engine comprising a naphthene base lubricating oil within the motor oil viscosity range containing about 0.1-2.0% by weight of lecithin and about 0.1-2.0% by weight of stannous sulfonate.

4. A Diesel lubricating oil adapted for crank case lubrication of a Diesel engine comprising a naphthene base mineral distillate lubricating oil within the motor oil viscosity range containing about 0.5% by weight of lecithin and about 0.5% by weight of a stannous soap selected from the group consisting of stannous naphthenate and stannous sulfonate.

5. The method of lubricating the bearings and cylinders of an internal combustion engine which comprises supplying to the bearings and cylinders of such engine a mineral lubricating oil within the motor oil viscosity range containing 0.1-2.0% by weight of a phosphatide compound and about 0.1-2.0% of a stannous soap selected from the group consisting of stannous naphthenate and stannous sulfonate, the oil being effective in reducing ring sticking and bearing corrosion and inhibiting varnish formation and oil ring sludge deposits.

6. The method of lubricating the bearings and cylinders of a Diesel engine which comprises supplying to the bearings and cylinders of such engine a naphthene base mineral distillate lubricating oil within the motor oil viscosity range containing about 0.1-0.5% of lecithin and about 0.5-1.5% of a stannous soap selected from the group consisting of stannous naphthenate and stannous sulfonate.
- 10 7. The method of preparing a motor oil adapted for the lubrication of the bearings and cylinders of an internal combustion engine, which comprises adding a stannous soap selected from the group consisting of stannous naphthenate and stannous sulfonate to a mineral lubricating oil at an elevated temperature of about 150° F. and below, mechanically agitating to form a solution, adding a phosphatide to said solution at said elevated temperature and mechanically agitating to form a homogeneous solution in the form of a mineral lubricating oil concentrate, and then adding the concentrate to the bulk of the mineral lubricating oil of motor oil viscosity range in a proportion to give by weight about 0.1-2.0% of the phosphatide and 0.1-2.0% of the stannous soap therein.
- 15 8. A lubricant comprising a mineral lubricating oil, a stannous soap and about 0.1-2.0% by weight of lecithin.
- 20 9. A lubricant comprising a lubricating oil, a metal salt of a carboxylic acid in an amount in excess of that which would be soluble in said lubricating oil and a phosphatidic material in an amount sufficient to render said first mentioned amount of said salt soluble in said oil.
- 25 10. A lubricant as claimed in claim 9 wherein the phosphatidic material comprises lecithin and cephalin.
- 30 11. A lubricant as claimed in claim 9 wherein the phosphatidic material comprises cephalin.
- 35 12. A lubricant as claimed in claim 9 wherein the phosphatidic material comprises lecithin.
- 40 13. A lubricant comprising a lubricating oil, a metal salt of an aliphatic acid in an amount in excess of that which would be normally soluble in said lubricating oil, and a phosphatidic material in an amount sufficient to render said first-mentioned amount of metal salt soluble in said oil.
- 45 14. A lubricant comprising a lubricating oil, a group II metal salt of an aliphatic acid in an amount in excess of that which would be normally soluble in said lubricating oil, and a phosphatidic material in an amount sufficient to render said first-mentioned amount of metal salt soluble in said oil.
- 50 15. A process for improving a lubricating oil comprising incorporating with said oil a metal salt of an aliphatic acid in an amount in excess of that which would be normally soluble in said lubricating oil, and a phosphatide in an amount sufficient to render said first-mentioned amount of salt soluble in said oil.
- 55 16. A process for improving a lubricating oil comprising incorporating with said oil an alkaline earth metal stearate in an amount in excess of that which would be normally soluble in said lubricating oil, and a phosphatide in an amount sufficient to render said first-mentioned amount of salt soluble in said oil.
- 60 17. A lubricant comprising a lubricating oil, a polyvalent metal soap in an amount in excess of that which would be normally soluble in said lubricating oil, and a phosphatidic material in
- 65 70 75

an amount sufficient to render said first-mentioned amount of said soap soluble in said oil.

18. A lubricant comprising a mineral lubricating oil, 0.1-4.44% by weight of a polyvalent metal soap, and a phosphatide in amounts sufficient to increase the solubility of said polyvalent metal soap in said mineral lubricating oil.

19. A lubricant comprising a mineral lubricating oil, 0.1-4.44% by weight of a polyvalent metal
